[57] CLAIM

The ornamental design for a combined bank and photograph holder, as shown and described.

DESCRIPTION

FIG. 1 is a front, perspective view of a combined bank and photograph holder showing my new design;

FIG. 2 is a back elevational view thereof;

FIG. 3 is a right side elevational view thereof.

The view of the left side is the same as that shown in FIG. 3 for the right side. The bottom half shown in FIG. 3 is also identical on both sides, on the left or right.
